UNITED STATES PATENT OFFICE.

JACOB S. KERN, OF FLEETWOOD, PENNSYLVANIA, ASSIGNOR TO FLEETWOOD METAL BODY COMPANY, OF FLEETWOOD, PENNSYLVANIA.

LATCH DEVICE FOR FOLDING DOORS.

1,271,582.

Specification of Letters Patent.

Patented July 9, 1918.

Application filed October 11, 1917. Serial No. 195,953.

To all whom it may concern:

Be it known that I, JACOB S. KERN, a citizen of the United States, residing at Fleetwood, in the county of Berks and State of Pennsylvania, have invented certain new and useful Improvements in Latch Devices for Folding Doors, of which the following is a specification.

This invention relates to a latch device for folding doors.

The primary object of this invention is to provide a latch device of this character which is simple and economical in construction and highly efficient and convenient in operation.

With the foregoing and other objects in view that will appear as the nature of the invention is better understood, the same consists in the novel features of construction, combination and arrangement of parts illustrated in the drawings, and more particularly pointed out in the appended claims.

In the accompanying drawings:

Figure 1 is a plan view illustrating the application of my invention with the folding door closed.

Fig. 2 is a similar view with the folding door partially open.

Fig. 3 is an outside elevation of the latch device, looking at right angles to Fig. 1, the car body and folding door indicated in dotted lines and only fragmentarily.

Fig. 4 is an end view of the latch device in closed or locked position, parts shown in section.

Fig. 5 is a similar view of the latch device, showing the position of the hinged member just before actuating or throwing the latch lock, and Fig. 6 is a vertical transverse section taken on the plane indicated by the dotted lines 6-6 of Fig. 4, looking in the direction indicated by the arrows.

Referring to the drawings for a more particular description of the invention, and which drawings are for illustrative purposes only, and are therefore not drawn to scale, the device comprises a stationary member 1 and a movable member 2 which is hinged to the stationary member.

The stationary member 1 comprises a flat metal elongated bar 3 which is countersunk in a longitudinal recess 4 in one edge of the frame 5 (which may be an automobile body)

and is fastened in place by the fastening screws 6 or other equivalent means.

55

The inner end of the bar 3 is formed with an approximately rectangular oblong flange or abutment 7 which extends or projects beyond opposite side edges of said bar and provides a stop or abutment for the hinged member of the device when the door is closed.

60

A latch bar 8 formed of a thin strip of spring steel or other metal possessing the required spring or resiliency, is arranged beneath the bar 3 with one end of the latch bar riveted or otherwise secured, as at 9, to the latter and its opposite or free end passing through and slightly beyond a transverse opening or slot 10 formed in the flange or abutment 7 and terminating in a catch 11. The latch bar is further equipped with a releasing head or button 12 which works in a corresponding opening or aperture 13 formed in the bar 3 and normally extends slightly above the plane of the outer face thereof for convenience in engaging by the thumb of the operator.

70

75

The free end of the latch bar 8 is adapted to be held at certain times in releasing position by the recessed head 14 of a locking device 15, also comprising a cylindrical rod or stem 16 mounted for endwise or longitudinal movement in the bearing lugs 17 formed on the inner face or wall of the flange or abutment 11 of the bar 3.

80

Disposed around the rod or stem 16 of the locking device is a coil expansion spring 18, the tendency of which is to retract or throw the locking device into operative or locking position. One end of said coil spring, as shown, bears against one of the bearing lugs 17, while its opposite end bears against a collar 19 secured on the rod or stem 16.

90

The movable section 2 of the latch device is hingedly connected to a horizontal offset arm 20 extending from the outer end of the flange or abutment 7 of the bar 3 of the stationary section, for which purpose the outer wall 21 of the movable section may be formed with a pair of parallel offset ears 22 and 23, which straddle the arm 20 and through which the latter passes the connecting screw 24. It will be observed that the ear 23 is provided with a projecting lip 25, the outer flat edge, as 26, of which, is

95

100

105

adapted to engage the outer end of the rod or stem 16 of the locking device 15 when the door is swung nearly open, as illustrated in Figs. 2 and 5 of the drawings.

5 In practice, to open the door, the operator depresses the releasing head or button 12 by the thumb which disengages the catch 11 with the upper edge 28 of the slot 10 in the folding section, 2, of the latch device. 10 When the free end of the latch bar 8 is thus depressed, the locking device 15 is caused to retract or spring back into operative or locking position, in which case the recessed portion 29 of the head 14 engages the adjacent edge of the latch bar 8 and holds the latter in releasing or inoperative position, as indicated in Fig. 5, until the folding door is swung open to a sufficient extent to bring the flat edge 26 of the lip 25 into contact 15 or engagement with the outer end of the stem 16 of the locking device 15, as indicated in Figs. 2 and 5, when a further movement of the door throws back or projects the locking device against the action of the coil 20 spring 18 into inoperative position, as indicated in Fig. 4, thereby releasing the free end of the latch bar 8 and permitting it to spring back into operative or locking position. Under these conditions when the door 25 is again closed, the catch 11 again engages the upper edge 28 of the slot 10 in the folding section 2, and locks the folding door in closed position until the releasing button 12 is again depressed by the operator. 30

35 The objection to most of the fixtures now on the market is that they require a pressure on both springs at the same time, and unless pressed far enough either one side or the other, it is impossible to fold them. By my invention, the operator is enabled to press one spring in at a time, and it will stay in until the door has been folded out when it will automatically release the spring so that when the door is again closed it will be 40 locked in its proper place.

45 From the foregoing description taken in connection with the drawings, it is thought that the construction, operation and advantages of this invention will be readily understood without requiring a more extended explanation.

Various changes in the form, proportions and minor details of construction may be resorted to without departing from the prin-

ciples or sacrificing any of the advantages 55 of this invention as defined in the appended claims.

Having described my invention, what I claim as new and desire to secure by Letters Patent, is:

60 1. In a latch device for folding doors, said latch device comprising stationary and hinged sections, a latch bar secured to the stationary section and coöperating with the hinged section to lock the door when closed, manually operated means for throwing the latch bar into releasing or inoperative position, a locking device for holding said latch bar in releasing position and means for disengaging said locking device with said latch 65 bar at a predetermined period, in the operation of opening said door.

65 2. In a latch device for folding doors, said latch device comprising stationary and hinged sections, a latch bar secured to the stationary section and coöperating with the hinged section to lock the door when closed, manually operated means for throwing the latch bar into releasing or inoperative position, a spring controlled locking device for 70 holding said latch bar in releasing position and means for disengaging said locking device with said latch bar at a predetermined period in the operation of opening said door.

75 3. In a latch device for folding doors, said latch device comprising stationary and hinged sections, a latch bar secured to the stationary section and coöperating with the hinged section to lock the door when closed, manually operated means for throwing the latch bar into releasing or inoperative position, a spring controlled locking device for holding said latch bar in releasing position, said locking device comprising a recessed 80 head adapted to engage the latch bar and a rod or stem slidable on the hinged section and means on the hinged section adapted to engage said rod or stem and disengage the locking device with the latch bar at a predetermined period in the operation of opening the door.

85 In testimony whereof I affix my signature in the presence of two witnesses.

JACOB S. KERN.

Witnesses:

CLARA HILBERT,
JACOB J. SHAFFER.
